ELEVATOR

Albert H. Beal and Jasper A. Hardcastle,
Houston, Tex., assignors to Speed and Service
Iron Works, Houston, Tex., a corporation of
Texas

Application March 1, 1934, Serial No. 713,509

1 Claim. (Cl. 294—90)

This invention relates to an elevator, and has particular relation to that type of elevator particularly designed for use in handling sections of pipe and the like about a derrick in well drilling operations.

An object of the invention is to provide an elevator comprising arcuate jaws hinged or pivoted together so that when in closed position they will fit closely around the pipe to be handled, with means for securely locking the jaws around the pipe while the pipe is being lifted, said locking means also being adapted to lock the jaws in open position when the jaws are opened to release the pipe.

Another object of the invention is to provide an elevator of the character described having means arranged to lock the jaws in holding position around a pipe and whereby a joint or section of pipe may be readily handled about a derrick in drilling operation, said locking means being automatically releasable when the load on the lifting cable is released so as to permit the jaws to open.

With the above and other objects in view, the invention has particular relation to certain novel features of construction, operation and arrangement of parts, an example of which is given in this specification and illustrated in accompanying drawing, wherein:

Figure 1 shows a plan view of the elevator showing the pipe engaging jaws closed and locked in closed position.

Figure 2 shows a side view thereof.

Figure 3 shows an end view.

Figure 4 shows a plan view partly in section, showing the pipe engaging jaws in open position.

Figure 5 shows a side view, showing the parts in the position shown in Figure 4, and

Figure 6 shows a side view of the device in use as applied to a section of pipe to be handled.

Referring now more particularly to the drawing wherein like numerals of reference designate similar parts in each of the figures, the numerals 1 and 2 designate arcuate complementary pipe engaging jaws which are pivoted together by means of a pivot pin 3. The pivoted end of the jaw 1 is extended and formed into a frame 4 having a rectangular opening 5 therethrough forming a bearing and the pivoted end of the jaw 2 is formed with an extension 6 which extends

through said opening 5 and which has the rearwardly extended overhanging flange 7. The frame 4 has a suitable grip 8 for handling the elevator and the jaw 2 has a grip 9 whereby said jaw may be swung open or closed.

There is a yoke 10 of an inverted U-shaped form and having the depending side arms 11, 12 which embrace the frame 4 and are pivoted to an upward extension 13 thereof by means of the transverse pivot pin 14. This yoke has an upstanding eye 15 for the attachment of the cable 16 thereto.

The free end of the arm 11 has a forwardly extended hook 17 for a purpose to be hereinafter stated.

In use, the cable 16 is attached to the eye 15 and operates over a sheave in the crown block 18 of the derrick 19. The cable is operated by means of the cat head 20 of the conventional draw-works 21. The yoke 10 may be swung forwardly a sufficient distance to cause the hook 17 to clear the extension 6 and the jaw 2 may then be swung open and then closed about the pipe to be handled and the cathead 20 operated to lift the elevator and load. The free ends of the arms 11 and 12 will be located outside of the extension 6 as shown in Figures 1 and 2 and the jaws will be locked around the pipe to be handled and by manipulating the cathead 20 the load may be lifted about the derrick and located at any place desired.

If it be desired to lock the jaws in open position the yoke may be swung forwardly until the hook clears the extension 6 and the corresponding jaw 2 then opened and the yoke then swung rearwardly to engage the hook 17 between the extension 6 and the frame 4, as shown in Figures 4 and 5.

It is desirable to limit the range of movement of the yoke outwardly so as to maintain the elevator jaws as nearly as possible in a horizontal position while the load is being lifted and for that reason a stop 22 has been provided on the frame 4 to so limit the range of movement of the yoke.

The drawing and description disclose what is now considered to be a preferred form of the invention by way of illustration only while the broad principle of the invention will be defined by the appended claim.

What we claim is:

An elevator comprising complementary arcuate clamp jaws pivoted together, the pivoted end of one jaw being extended and formed with an opening, a yoke pivoted on said extended end, an extension on the pivoted end of the other jaw

which works through said opening, said yoke having side arms arranged to embrace said extension when the jaws are closed and being movable to release the extension to permit the jaws to open.

ALBERT H. BEAL.
JASPER A. HARDCASTLE.
